United States Patent

Des. 240,737

Patented July 27, 1976

240,737

ELECTRONIC CALCULATOR

Lawrence Glen McCain, Beverly Hills, and Edward William Scott, Culver City, Calif., assignors to Rockwell International Corporation, El Segundo, Calif.

Filed July 10, 1974, Ser. No. 487,061

Term of patent 14 years

Int. Cl. D18—02

U.S. Cl. D26—5 C

FIG. 1 is a top plan view of an electronic calculator showing our new design.

FIG. 2 is a top plan view of a second embodiment thereof.

FIG. 3 is an end elevational view of both embodiments.

FIG. 4 is a side elevational view of both embodiments. The opposite side is identical thereto.

We claim:

The ornamental design for an electronic calculator, as shown and described.
